UNITED STATES PATENT OFFICE

132,133

DESIGN FOR A PLAQUE OR SIMILAR ARTICLE

William Olsen, New Haven, Conn., and Howard W.
Russell, Collingswood, N. J.

Application February 3, 1942, Serial No. 105,614

Term of patent 14 years

To all whom it may concern:

Be it known that we, William Olsen and Howard W. Russell, citizens of the United States, residing at New Haven, in the county of New Haven and State of Connecticut, and Collingswood, in the county of Camden and State of New Jersey, respectively, have invented a new, original, and ornamental Design for a Plaque or Similar Article, of which the following is a specification, reference being had to the accompanying drawing, forming part thereof.

The drawing is a perspective view of the plaque or similar article showing our new design.

We claim:

The ornamental design for a plaque or similar article, as shown.

WILLIAM OLSEN.
HOWARD W. RUSSELL.
